Albert P. Massey

UNITED STATES PATENT OFFICE.

ALBERT P. MASSEY, OF WATERTOWN, NEW YORK, ASSIGNOR TO THE EAMES VACUUM BRAKE COMPANY, OF SAME PLACE.

AUTOMATIC CAR-BRAKE.

SPECIFICATION forming part of Letters Patent No. 358,867, dated March 8, 1887.

Application filed October 22, 1886. Serial No. 216,926. (No model.)

To all whom it may concern:

Be it known that I, ALBERT P. MASSEY, a citizen of the United States, residing in the city of Watertown, in the county of Jefferson and 5 State of New York, have invented certain new and useful Improvements in Automatic Car-Brakes, of which the following, taken in connection with the accompanying drawing, is a specification.

10 My invention relates to automatic car-brakes.

In Patent No. 351,786, dated November 2, 1886, I have claimed two diaphragms or pistons opposed to each other by means of an intermediate lever, which changes the effective lever- 15 age of the diaphragms as they move the valve.

These improvements are for the purpose of a more sensitive action of the valves when actuated by similar diaphragms or pistons.

20 The drawing is a sectional view of the apparatus as designed for a system of vacuum-brakes.

A is a hollow valve-case connected through pipe A' with a reservoir in which a vacuum 25 is maintained by suitable means.

B and C are flexible diaphragms inclosing the ends of case A, and forming air tight joints therewith.

D is a space between diaphragm B and cover 30 E, which is connected by passage F with the train-pipe P. Chamber G is open to the atmosphere.

H is a bell crank or lever revolving about the fixed fulcrum J, and connected with the 35 two flexible diaphragms B and C by the links K and L.

M is an inclosed chamber connected by pipe Z with a brake diaphragm or cylinder.

N is a valve controlling the passage of air 40 between chamber M and case or reservoir A.

O is a valve controlling the passage of air between the chamber M and the atmosphere through openings U.

R is a flexible diaphragm for actuating valve 45 O, and is secured air-tight to its casing S.

T is a valve controlling the flow of air from casing S through passage W to case or reservoir A, and also from the atmosphere through passage V and passage W to casing S.

50 As shown, the valves are in running position and the brakes off.

The operation is as follows: When a train is running, a proper vacuum is maintained in the train-pipes and reservoir by means of suitable apparatus on the locomotive. When this is 55 the case, the diaphragm B has a vacuum on both sides and is in equilibrium, while the atmosphere pressing on the diaphragm C holds the levers, as shown. The valve T would be open between chamber S and reservoir A, 60 while the passage V would be closed. Therefore there would be a vacuum in chamber S, and valve O would be open to the atmosphere. If a little air is admitted to the train-pipe P, it decreases the vacuum in chamber D, so that 65 the atmospheric pressure on diaphragm C is no longer able to hold the bell-crank H, as shown. The bell-crank H will therefore begin to revolve around the fulcrum J and allow valve T to open passage V and close the passage X. This will allow the atmosphere to pass through V and W to chamber S and press the valve O on its seat, thus closing the opening between the brake-diaphragm and the atmosphere. A further motion of the bell-crank 70 H will bring the face H' in contact with the stem of valve N and open said valve, thus admitting air from the brake-diaphragm through chamber M to the case or reservoir A. This would begin to apply the brake. As the diaphragms B and C are connected to the bell-crank H at different angles, when H revolves to open valve N the leverage of diaphragm B 75 decreases while that of diaphragm C increases, so that there is always some point where they 80 will balance each other and come to a rest. As the vacuum in reservoir A decreases the bell-crank H revolves away from valve N until the valve seats itself, and the vacuum in the brake-diaphragm is maintained without further increase. In this position the bell-crank H 85 would be clear from the stems of both valves N and T. If the vacuum in the train-pipe is now increased, the vacuum in chamber D would be increased, and the atmospheric pressure on diaphragm C would cause the bell-crank H to 90 revolve against the stem of valve T and raise said valve, thus closing the passage V, and opening the passage X through W to S a vacuum would be formed in S, which would open valve O and admit air to the brake-diaphragm 95 to release the brakes. If the vacuum in the 100

train-pipe were reduced a little the brakes would be partially applied. If the vacuum in the train-pipe were reduced much the brakes would be applied fully. It is obvious that 5 these same functions would be performed by these valves with a fluid-pressure greater than the atmosphere if the valves seated in a reverse way. It is also obvious that pistons might be used instead of diaphragms to produce the same results.

What I claim, and desire to secure by Letters Patent, is—

1. In a fluid-pressure brake, a release-valve actuated directly by the fluid-pressure through 15 an auxiliary valve, which opens communication alternately between the diaphragm or piston which actuates said release-valve and the auxiliary reservoir, and between said diaphragm or piston and the atmosphere.

2. In a fluid-pressure brake, the combination of bell-crank H, valve T, and diaphragm R with suitable air ports or passages to actuate diaphragm R by fluid-pressure.

3. In a fluid-pressure brake, the combination of diaphragms B and C with bell-crank H and the detached valve N, substantially as described, and for the purpose set forth.

In testimony whereof I have signed my name to this specification, in the presence of two subscribing witnesses, on this 20th day of October, A. D. 1886.

ALBERT P. MASSEY.
